(57) **CLAIM**

The ornamental design for a plant grow light with fan, as shown and described.

DESCRIPTION

FIG. 1 is a front perspective view of a plant grow light with fan, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view showing the plant grow light with fan in a use state. The broken lines illustrate environment and form no part of the claimed design.
